Des. 192,018
Patented Jan. 2, 1962

192,018

CAKE SERVER

Charles A. McLeod, 162 E. Ohio St., Chicago, Ill.

Filed Aug. 15, 1961, Ser. No. 66,363

Term of patent 14 years

(Cl. D44—29)

FIG. 1

FIG. 2

FIG. 3

FIG. 4

FIG. 5

FIG. 6

FIG. 7

FIG. 1 is a front perspective view of a cake server embodying my new design;

FIG. 2 is a top plan view thereof;

FIG. 3 is a bottom plan view thereof;

FIG. 4 is a side elevational view of one side thereof;

FIG. 5 is a side elevational view of the other side thereof;

FIG. 6 is an end elevational view of one end thereof; and

FIG. 7 is an end elevational view of the other end thereof.

I claim:

The ornamental design for a cake server, as shown.
